UNITED STATES PATENT OFFICE.

WILLIAM L. MURPHY, OF NASHVILLE, TENNESSEE.

EVAPORATOR AND FURNACE.

SPECIFICATION forming part of Letters Patent No. 242,353, dated May 31, 1881.

Application filed August 5, 1880. (No model.)

To all whom it may concern:

Be it known that I, WILLIAM L. MURPHY, a citizen of the United States, resident at Nashville, in the county of Davidson and State of Tennessee, have invented certain new and useful Improvements in Evaporators and Furnaces; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

This invention has relation to evaporators; and it consists in the improved features of construction and combination hereinafter fully described, and particularly pointed out in the claims.

Figure 1 is a view, in perspective, of my improved evaporator. Fig. 2 is a central vertical longitudinal sectional view. Fig. 3 is a perspective view of an end-overflow pan, and Fig. 4 is a vertical longitudinal view of the same.

Referring by letter to the drawings, A designates the furnace, provided with a grate, B, lined with brick and pivoted centrally on the circular stand C. It is provided at each end with a wheel, the rear wheel, E, being larger than the front wheel, F. The wheels E and F serve a double purpose—viz., that of permitting the furnace to be turned so that it will have a proper draft and the ashes and cinders will not be blown into the contents of the pan; and, secondly, either of the wheels may be elevated by placing a plank or board between it and the ground, and scraping the dirt from beneath the wheel at the other end to give the pans the proper incline.

G designates the pan, having wooden sides and galvanized-iron bottom and ends. This pan is divided into from one to five, or more, compartments. Compartment 1 is formed along two sides and one end of the compartments 2, 3, 4, and 5 in a side-overflow pan, Figs. 1 and 2, and at one end of the pan in an end-overflow pan, Figs. 3 and 4. In the side-overflow pan the end partitions are made lower than the partitions H between the compartments, and an adjustable or detachable partition, I, is secured to the end partitions, J, and

the side partition, H, of compartment 2, so that it may be removed and replaced at pleasure. Bolts a and nuts b are employed to secure the removable partition I in place. In the end-overflow pan the partition K, between compartments 1 and 2, is made adjustable by securing a slotted wooden piece, L, to the partition K, so that the height of the partition may be increased or diminished at pleasure. Its height, however, need never exceed that of the other partitions, L, of the pan, but is usually set so that it is below their height. Communication is opened between the several compartments by means of elbow-pipes M, provided with strainers N, fitted on collars P in the partitions separating the compartments, so that they may be turned up to cut off communication between the compartments when necessary. Sliding gates or cut-offs may be employed for the same purpose, except between compartments 1 and 2, where the strainers must be employed to strain the juice as it flows from compartment 1 to 2.

I also employ with the evaporator an adjustable cooler, Q, consisting of a metal tray, R, provided with flanges S at each end and lined with brick, which I interpose between the fire and the bottom of the pan at either end thereof, as may be required for cooling the contents of the pan.

In operation the juice is let into compartment 1, and is permitted to spread over the entire bottom surface of the pan before building the fire in the furnace. The cooler is placed at the front end of the furnace, beneath the pan, to keep the juice coolest where it first enters the pan. Of course the cooler may be shifted to the other end of the furnace when it is necessary to cool the molasses, or a second cooler may be used at that point. The adjustable partition should be so arranged in the side-overflow pan that the partitions H will be the highest, and the elbow-pipe between 2 and 3 to cut off compartment 2 from 3. The fire is the hottest directly under compartment 2, and the boiling is most rapid in said compartment, so that the scum and froth boil over the lower partition into compartment 1, where it comes in contact with and floats upon the cooler or fresh juice which is kept running, and from which it can be readily skimmed. After the

juice has been partially boiled in compartment 2 it is passed into compartment 3, there boiled, thence to 4 and 5, in which it is finished, cooled, drawn off, and barreled. In the end-overflow pan the partition between compartments 1 and 2 is adjustable vertically, and is made lower than the others, in order that the froth, &c., may boil over into compartment 1. In the side-overflow pan, should the contents of any 10 of the compartments from 2 to 5 boil over, the froth, &c., will fall into compartment 1, where it may be skimmed off.

This construction of evaporator does not require the attention of one person all the time, 15 as in the old construction, where he must be kept constantly skimming, but affords ample time for the operator to attend to the mill, the furnace, and to skimming, thereby dispensing with the services of one man.

Having thus fully described my invention, 20 what I claim as new, and desire to secure by Letters Patent of the United States, is—

1. In an evaporator, the furnace mounted and pivoted upon the circular stand C, and provided with the wheels E and F at opposite 25 ends, as set forth.

2. In an evaporator, the pan provided with the compartments 1, 2, &c., having elbow-pipe and strainer between them to open and close communication, and the adjustable partition to 30 permit the overflow of froth, &c., constructed and operating substantially as set forth.

In testimony whereof I affix my signature in presence of two witnesses.

WILLIAM LEE MURPHY.
